UNITED STATES PATENT OFFICE.

HOMER J. DANA, OF PULLMAN, WASHINGTON.

PORTABLE HYDRAULIC POWER DEVICE.

1,343,117.

Specification of Letters Patent.

Patented June 8, 1920.

Application filed August 22, 1919. Serial No. 319,180.

To all whom it may concern:

Be it known that I, HOMER J. DANA, a citizen of the United States, residing at Pullman, in the county of Whitman and 5 State of Washington, have invented new and useful Improvements in Portable Hydraulic Power Devices, of which the following is a specification.

This invention relates to a reciprocatory 10 hand operated hydraulic device designed for applying a pushing or a pulling force to an object, and is especially adaptable for splitting logs and stumps or riving spruce, which work requires a pushing or driving force. 15 The object of the invention is to simplify and improve the existing art by producing a hydraulic power device of this character constructed of few parts which coöperate in such a manner as to accomplish the purpose 20 for which the device is constructed in an easier and more positive manner than has heretofore been accomplished.

Other objects and advantages will present themselves as the nature of the invention is 25 better understood, reference being had to the accompanying drawings, in which:

Figure 1 is an elevation, parts being in section of the improvement, illustrating the piston in its projected position.

Fig. 2 is a similar view but showing the piston in its retracted position.

Fig. 3 is a sectional view, substantially similar to Fig. 1, but illustrating a modification.

Fig. 4 is a similar view but showing the piston in its retracted position.

Fig. 5 is a sectional view through the four-way valve.

Fig. 6 is a detail perspective view of the 40 end of the piston rod provided with the cutting head.

As disclosed by the drawings the improvement comprises a cylinder 1 having therein a movable piston 2 provided with a piston rod 3, the latter projecting through a stuffing box 4 in one end of the cylinder. The piston 3 has its outer end provided with a cutting head which is preferably V-shaped in plan and which is designated by the numeral 5. Attached to the cylinder 1 by means of an angle duct 6 is a compensating chamber 7, the duct communicating with the head of the cylinder opposite that provided with the stuffing box through which 50 the piston rod 3 passes. The numeral 8 indicates a hydraulic force pump having pipes

or ducts 9 and 10 connected therewith, the said pipes being controlled by a hand operated four-way valve 11, the pipe 9 communicating with the cylinder through the head 12 thereof, and the pipe 10 likewise communicating with the cylinder through the head 13 thereof. Both the heads 12 and 13 are provided with relief valves 14 and 15 respectively.

Referring now particularly to Fig. 1, it will be seen that the piston is in extended position, the pump having been operated to fill the cylinder 1 with water, the pump and ducts being likewise filled with water and the compensating chamber 7 is filled with air at atmospheric pressure. The force pump 8 is operated to pump the water through the duct 9 from the rear end of the cylinder 1 into the front end through the duct or pipe 10, creating a pressure against the front side of the piston 2 which causes it to move toward the rear end of the cylinder and to draw the piston rod 3 into the cylinder. Since no water is ejected from the system, when the piston 2 is fully retracted (see Fig. 2), the volume of water which fills the rear of the cylinder as in Fig. 1 must be disposed of. However, the volume in the front end of the cylinder with the piston retracted is partly filled by the volume of the piston rod 3 and for this reason there is a surplus of water equal to the volume of that part of the piston rod which is drawn into the cylinder and this surplus is crowded into the compensating chamber 7 against the pressure of the air already filling it. The volume of the compensating chamber 7 is somewhat in excess of the volume of water displaced by the piston rod so that when the piston 2 is retracted the compensating chamber contains air and water under pressure.

To reverse the machine the four-way valve 11 is turned from the piston shown in Fig. 1 to that shown in Fig. 2. The pump is operated so that the water is drawn from the front end of the cylinder 1 and forced into the rear end thereof, forcing the piston 2 to travel forward and pushing the piston rod 3 out of the cylinder. As the piston 2 moves forward the water displaced in the front end of the cylinder is not sufficient to fill the volume created in the rear, since part of the volume in the front end of the cylinder was occupied by the piston rod 3. This deficiency in water is supplied by the

inflowing of water in reserve in the compensating chamber 7. This inflowing is augmented by the compressed air which is confined in the compensating chamber. If the pumping is continued the piston will travel to the position shown in Fig. 1 again, the rear of the cylinder will be filled with water and the compensating chamber will contain only air.

10 The compression of the air in the compensating chamber is only an incident in the operation of the machine and is not designed to act as a restoring agent for the purpose of extending the piston after it has been retracted. Again referring to Fig. 1, we will assume the piston rod 3 to have its head 5 contacting with some form of resistance to the rearward movement, such as a stump which is to be pulled. Upon the operation of 20 the pump 8 the water is pumped from the rear end of the cylinder and discharged into the front end, causing the piston 2 to move rearwardly drawing with it the piston rod 3. However, the water displaced by the 25 rearward movement of the piston can not all be pumped into the front end of the cylinder, because part of this volume is already occupied by the piston rod 3. This excess of water is therefore crowded into the compensating chamber 7, against the resistance of 30 the air already filling it. However, in the front end of the cylinder there will be a solid volume of water exerting pressure against the piston 2 and this performs the work 35 against the resistance, such as the pulling of the stump.

Again referring to Fig. 2, we will assume the piston rod to engage some form of resistance to its outward travel. This might be 40 the resistance of a log to the insertion of a wedge. The pump draws the water from the front end and forces it into the rear end of the cylinder and in so doing exerts a force against the rear face of the piston 2. There 45 is always an equal force exerted upon the compensating chamber which will counteract the ejecting force of the compressed air confined within it. If the pump develops sufficient force in the rear end of the cylinder 50 the air in the compensation chamber will be further compressed, allowing a greater volume of water to enter it, thus increasing the deficiency of the water in the cylinder. When this continues the pump will 55 tend to create a vacuum in the front end of the cylinder and if continued long enough it will succeed in creating a vacuum and stop the action of the pump entirely, as a hydraulic pump will not work against a vacuum.

60 This is relieved by opening the relief valve 15 and admitting air to the front end of the cylinder which allows the water to run into the pump and allow the latter to resume its normal operation until all of the water is 65 exhausted from the front end of the cylinder.

If the volume of the compensation chamber is but very little in excess of the volume of the piston rod then the piston can always be forced out to almost its fully extended position. Upon reversing the machine it can 70 be restored to normal by leaving the relief valve 15 open until all of the air that has previously been admitted has been expelled by the inflowing water. This is accomplished by locating the relief valve 15 close 75 to the top of the cylinder, and by attaching the duct or pipe 10 down low so that its mouth will be covered with the water as long as there is water in that end of the cylinder. This is also true with respect to the location 80 of the relief valve 14 and the mouth of the duct 9.

In the pulling operation there is no air cushion in the working end of the cylinder, and for each stroke of the pump there must 85 be a corresponding movement of the piston. In the splitting operation there is an air cushion in the end of the cylinder performing the work and for most uses to which the machine can be put, this air cushion is objectionable. Therefore, as illustrated in 90 Figs. 3 and 4 of the drawings, the compensation chamber 7' is attached to both ends of the cylinder 1' by means of ducts 16 and 17, the same being provided with valves 18 and 95 19 respectively, the said ducts communicating with the cylinder 1' directly above the relief valves 14' and 15'. The ducts 9' and 10' communicate with the opposite ends of the cylinder in the same manner as illustrated in Figs. 1 and 2 of the drawings, the 100 said ducts being under the control of a four-way valve 11' and being also connected to the force pump 8'. When this machine is employed for pulling the valve 19 is closed and 105 the valve 18 is opened, thus putting the compensation chamber and air cushion in connection with the rear end of the cylinder 1'. For the splitting operation the valve 18 is opened and the valve 19 is closed, connecting 110 the compensation chamber with the front end of the cylinder, and thus traversing the air cushion from the working or pressure end to the opposite end of the cylinder. The operation of the machine with this connection is 115 essentially the same as where the arrangement heretofore described is employed for pulling work. The addition of the valves 18 and 19 and the duct 17 facilitates the adaptation of the machine to operate most effectively either as a splitter or as a puller, although either arrangement will perform both functions successfully if the necessary manipulation of the relief cocks is carried out.

Having thus described the invention, what is claimed as new, is:

1. In a portable hydraulic power device, a cylinder, a piston therein and a piston rod therefor projecting through one end of a 120

cylinder, a compensating chamber, a valved duct connecting said chamber to the cylinder to the rear of the piston, a source of fluid supply, a pump therefor, ducts from said pump connected to the ends of the cylinder, 5 a four-way valve controlling said ducts, and relief valves in the ends of the cylinder.

2. In a portable hydraulic power device, a cylinder, a piston therein having a piston rod projecting through one end of the cylin- 10

der, a compensating chamber arranged over the cylinder, valved ducts connecting said chamber to the ends of the cylinder, a source of fluid supply, a pump therefor, ducts from said pump connected to the ends of the cylinder, 15 a four-way valve controlling said ducts, and relief valves in the ends of the cylinder.

In testimony whereof I affix my signature.

HOMER J. DANA.
